[57] CLAIM

The ornamental design for a golf club holder, as shown and described.

DESCRIPTION

FIG. 1 is a front perspective view of a golf club holder showing my new design;

FIG. 2 is a rear elevational view thereof;

FIG. 3 is a left side elevational view thereof;

FIG. 4 is a top plan view thereof; and

FIG. 5 is a bottom plan view thereof.

The broken lines showing the golf club and the grass are for illustrative purposes only.
